UNITED STATES PATENT OFFICE.

JOHN FRASER, OF SIMCOE, ONTARIO, CANADA, ASSIGNOR TO HIMSELF AND
G. A. UPPER, OF SAME PLACE.

VEHICLE-BRAKE.

SPECIFICATION forming part of Letters Patent No. 398,958, dated March 5, 1889.

Application filed October 30, 1888. Serial No. 289,494. (No model.) Patented in Canada October 13, 1888, No. 29,984.

To all whom it may concern:

Be it known that I, JOHN FRASER, of Simcoe, in the Province of Ontario and Dominion of Canada, have invented new and useful Improvements in Vehicle-Brakes, (for which I have obtained a patent in Dominion of Canada, No. 29,984, October 13, 1888,) of which the following is a full, clear, and exact description.

10 My invention relates to an improvement in vehicle-brakes, and has for its object to provide a brake of simple, durable, and effective construction, and capable of automatic application; and the further object of the invention is to provide a brake which will not only lock the wheels when the vehicle is descending a hill, but which will also lock the wheels in the event the vehicle should be stopped in ascending a hill.

20 The invention consists in the novel construction and combination of the several parts, as will be hereinafter fully set forth, and pointed out in the claims.

Reference is to be had to the accompanying drawings, forming a part of this specification, in which similar figures of reference indicate corresponding parts in all the views.

25 Figure 1 is a plan view of the brake applied to the front wheels of a vehicle. Fig. 2 is a longitudinal section taken partially on line *x x* of Fig. 1. Fig. 3 is a partial side elevation of a wheel, illustrating the brake-shoe in position to lock the said wheel in ascending a hill; and Fig. 4 is a transverse section on line *y y* of Fig. 2.

30 The tongue 10 of the vehicle is secured in any approved manner between the forward extremities of the forward hounds, 11, which hounds are connected at the back by a cross-bar, 12. A clevis, 13, is secured to the forward end of the tongue 10, and a vertical yoke, 14, provided with eyes at its ends, is pivoted upon the tongue through the medium of a bolt, 15, passing through the yoke and the 35 clevis below the tongue, as best illustrated in Fig. 4.

40 Forward of the axle 16 a lever, 17, is centrally pivoted to the outer side of each section of the forward hounds, as illustrated in Fig. 1, the said levers being provided with an aperture, 18, at the top, and a similar aper-

ture, 19, at the bottom end. A rod, 20, is pivoted to the lower end of the yoke 14, which rod extends rearwardly beneath the tongue 10, passing through an eye, 21. Rods or links 22 and 23 are attached to the rear extremity of the rod 20, which links or rods are carried rearwardly to a connection with the lower ends of the levers 17, as best illustrated in Fig. 1.

45 The tongue 10 is provided with a slot, 24, in which the bolt 25, carrying the doubletree 26, is held to reciprocate. The main arm of the doubletree is provided with a staple from which two lengths of chain 27 are projected, the said chain being attached to upper links or rods, 28, which upper links or rods are connected to the upper extremities of the said levers 17. If preferred, instead of the tongue being slotted as shown, the slot may be made in the doubletree.

50 A brake-arm, 29, is pivoted at one end to each extremity of the cross-bar 12, and a brake-shaft, 30, is centrally passed through the said brake-arms 29 and held in position by means of collars 31. The lower ends of the brake-arms 29 are connected with the lower ends of the side levers, 17, by rods or chains 32. Upon the extremities of the brake-shaft 30 a brake-shoe, 33, is rigidly mounted, 55 which brake-shoe is provided with a concave face, 34, and an opposing convex face, 35, the shaft 30 being made to pass through the shoe at or near the upper or convex end, as best illustrated in Fig. 3. The lower end of the 60 shoe 33 is made to terminate in a point, to which point a jack-chain, 36, is secured. Both the concave and convex faces of the brake-shoe are covered with leather or other similar material. The brake-shoes normally are held 65 out of engagement with the wheels.

65 It is evident that when the horses hold back and draw upon the upper end of the yoke 14 the brake-arms 29 are drawn forward, and the brake-shoes are consequently brought in frictional contact with the rear of the forward wheels, and that when the horses start forward the doubletrees will also move forward, drawing the upper ends of the levers 17 in the same direction, which movement will 70 carry the brake-arms 29 outward and relieve the wheel from contact with the brake-shoes.

When the wheels are moved forward, the 5
brake-shoe will roll to such an extent as to
bring the concave face of the shoe flush with
the tire of the wheel. When backing up, the
reverse motion of the wheels rolls the said
concave face back and brings the top or con-
vex face with the shaft toward the wheel.
The block, however, does not in this position
bind the wheel, as the force at the neck-yoke
10 is exhausted.

To block the wheels in going up a hill, the
jack-chain attached to the brake is hooked in
the stake ordinarily attached to the bolster of
the vehicle; then the driver with a slight pull
15 upon the chain can turn the brake over with
the convex face up, so that it will be brought
in decided contact with the wheel. Both
brakes will turn together, as they are both
mounted on the same shaft. When the vehicle
20 stops and the wheels begin to move back,
the convex face of the brake-shoe binds the
wheels as the outward movement of the shaft
30 is limited by the connecting rods or links 32.

I desire it to be distinctly understood that
25 while I have illustrated the brake as used in
connection with a farm-wagon it may be em-
ployed in connection with any type of vehicle.

Having thus described my invention, I claim
30 as new and desire to secure by Letters Patent—

1. The combination, with a vehicle having a
yoke pivoted on the forward end of its tongue,
of pivoted levers, reversible brake-shoes piv-
oted in said levers, and a connection between
35 the said yoke and the lower ends of the le-
vers, substantially as described.

2. The combination, with a vehicle having a
yoke pivoted on the forward end of its tongue,
of pivoted levers, a shaft loosely mounted in
the said levers, brake-shoes having opposing 40
concave and convex bearing-faces and se-
cured to the ends of the said shaft, and a
connection between the lower ends of the le-
vers and yoke, substantially as herein shown
and described.

3. In a vehicle-brake, the combination, with
the forward hounds, the tongue, and a double-
tree having a sliding movement on the tongue,
of a yoke pivoted on the forward end of the
tongue, levers pivoted to the hounds in rear 50
of the axle, a shaft loosely mounted in said
levers, brake-shoes having opposing concave
and convex bearing-faces, levers pivoted to
the hounds in front of the axle and having
their upper ends connected to the doubletree 55
and their lower ends to the yoke and to the
levers in rear of the axle, substantially as
herein shown and described.

4. In a vehicle-brake, the combination, with
the tongue, of the clevis 13, secured to the 60
forward end of the tongue, and the yoke 14,
through which the tongue projects, provided
with eyes at its ends and pivoted to the clevis
by the bolt 15 passing through the yoke and
clevis below the tongue, substantially as 65
herein shown and described.

JOHN FRASER.
